(57) **CLAIM**

The ornamental design for a combined vaporizer tamp and pick tool, as shown and described.

DESCRIPTION

FIG. 1 is a front perspective view of a combined vaporizer tamp and pick tool showing the claimed design;

FIG. 2 is a front view thereof;

FIG. 3 is a rear view thereof;

FIG. 4 is a right side view thereof; the left side view being a mirrored image thereof;

FIG. 5 is a top view thereof;

FIG. 6 is a bottom view thereof;

FIG. 7 is an exploded front perspective view of the combined vaporizer tamp and pick tool of FIG. 1; and,

FIG. 8 is a front perspective view of the combined vaporizer tamp and pick tool of FIG. 1 in an alternate position.

The broken lines in the figures illustrate portions of the combined vaporizer tamp and pick tool or environmental structures and form no part of the claimed design.
